UNITED STATES PATENT OFFICE.

CASSIUS F. BLACKLIDGE, OF WASHINGTON, DISTRICT OF COLUMBIA.

TYPOGRAPH APPARATUS.

943,614.

Specification of Letters Patent. Patented Dec. 14, 1909.

Application filed July 8, 1909. Serial No. 506,552.

To all whom it may concern:

Be it known that I, CASSIUS F. BLACKLIDGE, a citizen of the United States, residing at Washington, in the District of Columbia, have invented certain new and useful Improvements in Typograph Apparatus; and I do hereby declare the following to be a full, clear, and exact description of the invention, such as will enable others skilled in the art to which it appertains to make and use the same, reference being had to the accompanying drawings, and to the letters and figures of reference marks thereon, which form a part of this specification.

This invention relates to new and useful improvements in typographs or apparatus adapted to print photographically letters, characters, etc., and means for spacing the same.

The invention consists more specifically of a typograph apparatus in which a yielding negative is provided which is held under pressure against the face of the photographic printing paper during the exposure of the negative, means being provided for applying the pressure as the shutter is moved into an exposing position.

The invention comprises various details of construction, combinations and arrangements of parts which will be hereinafter fully described and then specifically defined in the appended claims.

My invention is illustrated in the accompanying drawings, in which:

Figure 1 is a perspective view of my improved typograph apparatus. Fig. 2 is a perspective view showing the frame opened and illustrating the movable rack adapted to hold the printing paper. Fig. 3 is a sectional view on line 3--3 of Fig. 1. Fig. 4 is a sectional view on line 4--4 of Fig. 1. Fig. 5 is a sectional view on line 5--5 of Fig. 1. Fig. 6 is a detail view on line 6--6 of Fig. 1. Fig. 7 is a detail view on line 7--7 of Fig. 6. Fig. 8 is a detail sectional view showing the slide in its normal position, and Fig. 9 is a plan view of the film showing the alphabetical letters and numerals thereon.

Reference now being had to the details of the drawings by letter, A designates the frame of the apparatus which may be of any size or shape and is provided with a hinged cover A' upon which I have shown a rotatable negative B, made preferably of any yielding material, such as celluloid, and fixed

to rotate with the stub shaft C to which a hand wheel C', shown in Figs. 1, 4 and 7 of the drawings, is fixed. Said cover is provided with an exposing opening D which may be of any suitable shape and D' designates a shutter or slide which has preferably two circular outlined exposing apertures therein, which are designated in the drawings by letters d and d', in which the two exposing caps e and e' respectively are mounted, as shown clearly in Fig. 4 of the drawings. In the exposing opening D in said cover is mounted a metallic frame D² having flanges D³ and D⁴, the former of which project toward each other in the opening while the latter extend over the outer marginal edge of the cover. Mounted within the opening D of the cover is a movable transparent block, designated by letter E, and which in the present instance is shown as made up of sections, one of which has projecting ends E' which serve as flanges and contact with the flanges D³ and limit the movement of the block in one direction. Positioned immediately underneath said opening is the rotatable negative, shown clearly in Fig. 4 of the drawings in section and also in Fig. 6. Said slide has a longitudinal movement between the guideways D⁵ and one of said guideways is cut away as at D⁶ to disclose a sight aperture G in the cover and through which the markings upon the negative may be discerned through a ruby or other suitably colored glass or film.

H designates an indicating pointer which is fastened to the cover and has its pointer indicating midway the length of said sight aperture and opposite which point the character to be printed is adapted to be moved. A spring K bears yieldingly against the upper surface of the transparent block E and the under surface of the shutter, as the opening in the shutter is brought into registration with the opening D to cause the block to be moved downward under pressure and move the film underneath against the printing surface L upon the rack N, shown clearly in Fig. 2 of the drawings. The slide is preferably recessed away as at D⁶ in order to allow the springs I to normally rest and in which both the springs I and K are adapted to yield when the shutter is closed. When the shutter is opened, the springs I bearing against the springs K will cause the same to move toward and depress the transparent block and said block in turn, bearing yield-

ingly against the pliable film of the negative, will cause the latter to press against the surface of the printing paper and hold the same taut and in close contact with the printing surface while the exposure is being made.

In order to cause the lettering and figures upon the negative to be plainly discernible at the sight aperture, a plate, designated by letter D⁷ and shown in Fig. 8 of the drawings, and made preferably of white material is fastened to the under surface of the top and over a portion of the negative said strip, forming a white back ground.

The rack N, which has bales N' thereon for the purpose of holding the printing paper taut, has a transverse movement upon the carriage J, having flanges J' upon its opposite edges adapted to confine the rack between the same, and the carriage J has an adjusting bar J² which extends through an aperture in the side of the frame and has its outer end J³ angled, forming means whereby the bar may be moved longitudinally and with it the carriage in order to bring the rack N in different positions relative to the exposing aperture in the cover. Said rack has a longitudinal groove I' along one of its marginal edges in which a rod I² passing to the bar I³ is adapted to engage in order to cause the rack to move with the bar I³ as the latter is moved at right angles to the movement of the carriage.

An adjusting bar P is fastened to the bar I³ and extends through a slot in the side of the casing and is movable upon the raised portion P' of the shelf A³ which projects from the casing A, as shown clearly in Figs. 1 and 2 of the drawings. Said bar P has an upturned end P² forming a handle whereby said bar may be moved longitudinally and it is also provided with a rack bar P⁴ along one marginal edge thereof adapted to engage the teeth of the pinion R which is journaled upon the stud R'. The teeth of said gear register with the teeth of the rack bar, and R² designates a ratchet wheel fixed to said stud and gear wheel, and R³ is a swinging pointer pivotally mounted upon said stud and adapted to register over the scale R⁵ upon said shelf. R⁵ is a spring-actuated pawl pivotally mounted upon the shank of said pointer and adapted to engage the teeth of the ratchet wheel and forming means whereby, as the pointer is swung in one direction, a rotary movement will be imparted to the ratchet wheel but, when the pointer is swung in the opposite direction, the pawl will turn idly over the teeth of the ratchet wheel. It will be noted upon reference to the drawings that there are two concentric series of numerals arranged upon said scale, the outer series corresponding with the outer series of alphabetical letters S upon the negative, while the inner series of numerals upon the scale indi-

cate the inner concentric series of letters of the alphabet which are of a smaller scale than each outer series.

It will be noted upon reference to Fig. 9 of the drawings that opposite each letter in each series of the alphabet is a numeral indicating a particular letter. For instance, in order to space the letters apart at proper intervals, the gear and ratchet wheels are required to be given a certain partial rotary movement. For instance, on the negative, the letter M is identified by numeral 6, indicating that the pointer in order to bring the letter M in the outer series underneath the exposing opening is moved to the left until this pointer comes opposite the numeral 6 and then, by giving the pointer a swinging movement clockwise until it contacts with the stop T, the sensitized printing surface will be moved in proper position to be printed upon. The letter I, which is narrower than the other letters, for instance is identified by numeral 1, thus indicating that the indicating pointer, in order to bring the sensitized printing paper into proper position, should be moved opposite the numeral 1 upon the scale and thence swung clockwise until the pointer contacts with the stop. Said stop T has a pivotal movement and, when it is utilized for indicating letters in the inner concentric series upon the negative, is turned at right angles to the position it assumes when adjusted for use in connection with the pointer for indicating in the outer series of the alphabet, it being understood that, when the indicating pointer is utilized for spacing the letters in the outer series, the stop is turned at right angles to the position shown in Fig. 1 of the drawings and out of the path of the pointer.

The bar J² has a scale formed thereon in order to indicate opposite the apertured plate J⁵ upon the end of the frame the distance it may be desired to move the carriage in either direction, while the indicating pointer serves to adjust the rack in a direction at right angles to the movement of the carriage. It will thus be noted that the rack has adjustments in two directions at right angles to each other.

In operation the sensitive printing paper is placed upon the rack and, by the manipulation of the two adjusting bars, is brought so that the printing will be done at the proper position upon the paper desired and, when the apparatus is ready to make the exposure, the shutter is moved longitudinally and, as the springs K come in contact with the springs L, the latter will force the transparent block against the film and cause the same to yield and be pushed down against the printing surface of the paper while the exposure is being made. When the shutter is closed by moving the same longitudinally, the springs will yield in the recesses and

pressure will be removed from the transparent block. In order to bring the first letter or character to be printed in proper position, the hand wheel C' is turned and with it the negative and, by watching at the sight aperture, it may be seen when the character to be printed comes on the pointer, after which the shutter is moved longitudinally and the transparent block depressed during the exposing interval only, thus insuring a close contact between the negative and paper.

What I claim to be new is:—

1. A typograph apparatus, comprising a casing, a sensitized photographic sheet contained therein, a flexible negative, a shutter, and means actuated by the movement of the shutter to cause a portion of the negative to flex against the sensitized sheet as an exposure is made.

2. A typograph apparatus, comprising a casing having an exposing aperture, a flexible negative mounted within the casing and adjacent to said aperture, a transparent block movable within said aperture, a shutter, and means actuated thereby and adapted to press the block against the negative and flex a portion thereof temporarily against the printing sheet as an exposure is made.

3. A typograph apparatus, comprising a casing having an exposing aperture, a flexible negative mounted within the casing and adjacent to said aperture, a transparent block movable within said aperture, a shutter, springs actuated by the movement of the shutter and adapted to move said block against the sensitized sheet of paper as the shutter is opened.

4. A typograph apparatus, comprising a casing having an exposing aperture, a flexible negative mounted within the casing and adjacent to said aperture, a transparent block movable within said aperture, a shutter, springs fastened to the casing and adapted to bear yieldingly against the outer face of said block as the shutter presses against said spring to cause the block to be moved against the negative and flexed temporarily a portion thereof against the printing surface of said sheet as the shutter is opened.

5. A typograph apparatus, comprising a casing having an exposing aperture, a flexible negative mounted within the casing and adjacent to said aperture, a transparent block mounted within said aperture, means for retaining said block within the latter, a spring fastened to the casing and projecting into said opening, a shutter engaging said spring and causing the block to be depressed against the negative to flex temporarily a portion thereof against the sensitized surface of said sheet as the shutter is moved to make an exposure.

6. A typograph apparatus, comprising a

casing having an exposing aperture, a flexible negative mounted within the casing and adjacent to said aperture, a transparent block mounted within said aperture, means for retaining said block within the latter, a spring fastened to the casing and projecting into said opening, a sliding shutter engaging said spring, their free ends extending into recesses formed in the under end of the shutter and adapted to contact with and causing said block to be moved against the surface of a sensitized sheet as the shutter is moved into an exposing position.

7. A typograph apparatus comprising a casing having an exposing aperture, a movable, flexible negative mounted adjacent to said exposing aperture in the casing, a sensitized sheet contained within the casing, means for moving said negative, a movable transparent block retained in said exposing aperture, a shutter, and means actuated thereby and adapted to move said block against the negative and flex temporarily a portion thereof against a sensitized sheet as the shutter is moved to make an exposure.

8. A typograph apparatus comprising a casing having an exposing aperture, a rotatable negative mounted within the casing, means for rotating the same, a shutter, a transparent block mounted in the exposing aperture of the casing, means actuated by the movement of the shutter for moving said block against a sensitized sheet as the shutter is actuated to make an exposure.

9. In combination with the casing of a typograph apparatus having an exposing aperture, a movable carriage therein, means for operating said carriage, a rack mounted upon the carriage and having a movement independent thereof, means for moving the rack, a flexible negative mounted within the casing adjacent to said exposing aperture therein, a movable shutter, a transparent block mounted in the exposing aperture, and means actuated by the movement of the shutter in making an exposure to cause the block to move against and flex a portion of the negative against a sensitized sheet adapted to rest upon said rack.

10. In combination with the casing of a typograph apparatus having an exposing aperture, a movable carriage therein, means for operating said carriage, a rack mounted upon the carriage and having a movement independent thereof, means for moving the rack, a rotatable flexible negative, having characters thereon identified by numerals, mounted within the casing adjacent to said exposing aperture therein, a bar fixed thereto having rack teeth upon an edge thereof, a pinion wheel in mesh with said rack teeth, a ratchet wheel fixed to the gear wheel, a swinging pointer, a pawl carried thereby and adapted to engage said ratchet teeth, a scale adjacent to which said pointer

4
is adapted to be moved and containing characters and numerals corresponding to those upon the negative, and a stop to limit the movement of said pointer.

- 5 11. In combination with the casing of a typograph apparatus having an exposing aperture, a movable carriage therein, a graduated bar fixed to said carriage and forming means for moving the same, a rack 10 mounted upon and having a movement independent of the movement of the carriage and adapted to contain a sensitized sheet of paper, a rotatable negative mounted adjacent to said exposing aperture in the casing 15 and having characters identified by numerals thereon, a shutter actuated thereby as it is exposed, to cause a portion of the negative to flex against the printing surface upon the rack, means upon the carriage for 20 guiding the rack, a bar connected to the rack and having rack teeth, a rotatable pinion meshing with said rack teeth, a ratchet wheel rotating with the gear wheel, a pivotal pointer, a pawl carried thereby and engaging the teeth of the ratchet wheel, a scale 25 having numerals and characters thereon adjacent to which said pointer moves, and means for limiting the movement of the pointer.
- 30 12. A typograph apparatus comprising a casing, a movable rack mounted therein and adapted to contain a sensitized sheet, a bar moving the teeth upon the edge of said bar, a rotatable pinion wheel meshing with said 35 teeth, a ratchet wheel movable with the pinion, a swinging dial mounted upon the pivot of the pinion, a pawl carried by said pointer and adapted to engage said ratchet wheel, a scale having numerals and letters in concentric circles thereon, means for limiting the 40 movement of said pointer, a cover hinged thereto provided with an exposing aperture, a flexible negative rotatably mounted upon said cover and closing said exposing aperture, and adapted to contain letters of the 45 alphabet in concentric series with the numerals indicating the relative spacing distance between the letters and corresponding with the lettering and numerals upon said dial, a shutter mounted upon the cover, and means 50 actuated by the shutter as an exposure is made for causing a portion of the negative to flex against a printing surface contained within the casing.
- 55 13. A typograph apparatus comprising a casing, a movable rack mounted therein and adapted to contain a sensitized sheet, a bar moving the teeth upon the edge of said rack, a rotatable pinion wheel meshing with said 60 teeth, a ratchet wheel movable with the pinion, a swinging dial mounted upon the pivot of the pinion, a pawl carried by said pointer adapted to engage said ratchet wheel, a scale having numerals thereon, a pivotal stop

adapted to allow said pointer to swing different distances in one direction, a cover hinged thereto provided with an exposing aperture, a flexible negative rotatably mounted upon said cover and closing said exposing aperture and adapted to contain 70 letters of the alphabet in concentric series with the numerals indicating the relative spacing distance between the letters and corresponding with the lettering and numerals upon said dial, a shutter mounted upon the cover, and means actuated by the shutter as an exposure is made for causing a portion of the negative to flex against a printing surface contained within the casing.

14. A typograph apparatus comprising a 80 casing, a cover with an exposing aperture, a flexible rotatable negative mounted upon the under surface of the cover, a shutter, means actuated by the latter as an exposure is made for causing a portion of the negative to flex, a printing surface within the casing, a carriage mounted within the latter, flanges upon said carriage, a rack mounted upon the carriage and guided by said flanges and having a movement independent 85 of the movement of the carriage, a bar turning substantially the length of the inner dimensions of the casing, a rod secured to said bar and adapted to engage said rack, a rack bar fastened to said rod carrying bar, a rotatable pinion meshing with said rack bar, a ratchet wheel fixed to the pinion, a pivotal pointer, a pawl carried thereby and adapted to engage said ratchet wheel, and means for limiting the movement of said 90 pointer.

15. A typograph apparatus comprising a casing having a laterally projecting shelf and a hinged cover with an exposing aperture and a sight aperture therein, a rotatable flexible negative mounted upon the under surface of said cover adjacent to said exposing aperture, a pointer mounted adjacent to said sight aperture, means for rotating said negative, a transparent block mounted in said exposing aperture, flanges adjacent to the edges of said exposing aperture and adapted to limit the inner movement of said transparent block, a shutter with an exposing aperture therein, means actuated by the shutter for moving said block against the negative to cause a portion thereof to flex against the printing surface, a rack within the casing, and means for moving the same to different positions 115 underneath the exposing aperture.

In testimony whereof I hereunto affix my signature in the presence of two witnesses.

CASSIUS F. BLACKLIDGE.
